UNITED STATES PATENT OFFICE.

ORVILLE D. ROGERS, OF SHOALS, INDIANA.

DESIGN FOR A BOX.

SPECIFICATION forming part of Design No. 22,462, dated May 23, 1893.

Application filed February 8, 1893. Serial No. 461,542. Term of patent 7 years.

To all whom it may concern:

Be it known that I, ORVILLE D. ROGERS, of Shoals, in the county of Martin, in the State of Indiana, have invented a new and ornamental Design for a Box, of which the following, taken in connection with the accompanying drawing, is a full, clear, and exact description.

My new design consists in a novel configuration of a box and is fully illustrated in the annexed drawing.

The configuration of my newly invented design for a box is as follows:—The bottom is flat and rectangular in shape, and at both lateral edges is continued upward, on one side only a short distance, and on the other being carried in a continuous curved surface forming sides and a top, and overlapping the be-

fore mentioned short continuation of the bottom. The ends are plane surfaces, closing the space between the flat bottom and the curved top and sides, and are located within the same so that the edges of the bottom and curved top project a short distance beyond the ends of the box.

Having thus described my design, what I claim is—

The design for a box, substantially as shown and described.

In testimony whereof I have hereunto set my hand this 4th day of November, 1892.

ORVILLE D. ROGERS.
